(57) CLAIM

An ornamental design for a undergarment as shown and described.

DESCRIPTION

FIG. 1 is a front view of an undergarment including the new ornamental design.

FIG. 2 is rear view of the undergarment of FIG. 1.

FIG. 3 is a right side view of the undergarment of FIG. 1.

FIG. 4 is a left side view of the undergarment of FIG. 1.

FIG. 5 is a top view of the undergarment of FIG. 1; and,

FIG. 6 is a bottom view of the undergarment of FIG. 1.

The broken lines shown in the drawings depict portions of the undergarment that form no part of the claimed design.
